UNITED STATES PATENT OFFICE.

MARIUS ROSGAARD, OF BROOKLYN, NEW YORK.

FIRE ESCAPE.

Application filed September 30, 1921. Serial No. 504,419.

To all whom it may concern:

Be it known that I, MARIUS ROSGAARD, a citizen of the United States, residing in Brooklyn, county of Kings, State of New York, have made a certain new and useful Invention in Fire Escapes, of which the following is a specification.

This invention relates to that class of fire escapes which is extensible and portable, and it is my object to provide a fire escape which may be supported on a suitable truck for quick transportation to the place of need and where it may then be quickly run up to any desired window or opening of a building from which persons are to be rescued.

A further object includes the provision of an extensible chute device which is provided with extension and adjusting means for elevating and adjusting the chute device as occasion may require.

Other objects will appear hereinafter, and I attain these objects by the mechanism illustrated in the accompanying drawings in which:

25 Figure 1 is a view of a side elevation wherein the chute is partially extended and partially elevated.

Fig. 2 is an end view.

Fig. 3 is a view of the bed plate and adjusting mechanism.

Fig. 4 is a view taken on lines 4—4 of Fig. 1, looking in the direction of the arrows.

Fig. 5 is a plan view of the bed plate showing the lateral and longitudinal adjusting mechanism.

Fig. 6 is a sectional view taken on lines 6—6 of Fig. 2.

Fig. 7 is a sectional view taken on lines 40 7—7 of Fig. 1.

Fig. 8 is a view of the end of the chute.

Similar numerals refer to like parts throughout the several views.

Referring now to the drawing, a bed plate 10 is suitably supported by castors or rollers 12 on a bearing plate 13, which bearing plate may be suitably fastened to the body 14, of a motor truck, or other means of conveyance. Supporting angle brackets 15 are securely fastened in a vertical position to the bed plate by means of bolts 16. Near the apex of the angle of each bracket there is provided a bearing surface 17 which carries the journal bearing 18 for the chute hereinafter described.

On the bearing plate 13 there is secured the laterally adjusting anchor block comprising an angle plate 19, on which are spaced uprights 20, which uprights are provided with bearing surfaces for carrying the drive worm 21. This worm engages with gear teeth 22 on the bed plate for lateral adjustment.

On a diameter of the bed plate but substantially parallel with the angle brackets 65 and approximately midway therebetween, there is secured the chute elevating block. This block, in a preferred form, consists of a main trough-shaped member 23 having smooth edges or tracks 24; a rear bearing 70 plate 25, and a front bearing and supporting plate 26. Journaled in the bearing plates is the drive worm 27, on which operates the elevating block 28 to slide back and forth on tracks 24 when the drive worm is operated. 75

Pivottally connected at one end to the elevating block, by screws or rivets 29 and 30, are the elevating arms 31 and 32. The other end of each of the elevating arms is pivotally connected to the chute block 33 80 for raising and lowering the outer end of the chute in the manner readily understood.

The chute consists, in a preferred form, of a main or bottom member 34 and a number of telescoping members 35, 36, 37, etc., 85 the upper section of which may be provided with safety hook *h*, and all the members are U- or trough-shaped, as is best illustrated by Figs. 4 and 7. The main member is composed of a number of united sections (a), 90 and a curved lower section (b). At the end of the lower section there is mounted the catch or collector basket 38, which may be folded and hooked in place as is indicated by the dotted lines, for moving or storing when 95 the apparatus is not in use.

The successive sections 35, 36, 37, etc., are each a little smaller than its preceding section, to telescopically slide one into the other, and all the sections are open at the upper side and section 35 is provided with bars or ladder rounds 39. The several sections are slidably held and guided by guide clamps 40, 41, 42, etc., and are moved, or expanded and contracted by the operation 105 of lazy-tongs 43 on either side.

The lazy-tongs comprise a number of short members C, C, etc., and a pair of longer members *f* and *g*, the latter of which is best illustrated by Fig. 4. These mem- 110

bers are pivotally united to the several movable telescopic sections at *g* and are operated by the inner and outer sectors *d* and *e* which are joined to the longer members at 5 *h*. Teeth on the outer curved surface of sectors *d* and *e* mesh with cogs on gears 44, and the sectors are held in proper relation by bearing rollers 45. These gears are operated by bevel gears 46 which in turn are 10 connected to drive shafts 47 and 48 for being operated by any suitable mechanism, as a worm drive 49. Connected to shafts 47 and 48 are bevel gears 50 and 51, respectively, for transmitting motion to shaft 48 15 through the agency of bevel gears 50, 51 and 52 in the manner well understood. It is obvious that in place of the operating handles 53, 54 and 55, suitable motors (not shown) may be used.

20 From the above description the use and operation of my invention is readily understood. If it is desired to use my device as a fire escape, the apparatus is rushed to a suitable position and under the opening from 25 which exit is to be made. The operating handle 54 is placed into operation to elevate the chute and at, or about the same time, handles 55 and 53, respectively, for adjusting and expanding the chute, are put into 30 operation. The upper end of the chute may rest on, or be hooked into the exit opening, and persons may then slide down the chute to be received in the safety basket which is then in the position shown in full lines in 35 Fig. 1.

Besides use as a fire escape, it is obvious 40 that my apparatus is also useful in conveying packages from elevated positions, as ships, warehouses, stores, etc., onto trucks 45 in a quick and efficient manner, and in all cases the apparatus is of size and construction to meet the conditions under which it is used.

While I have described a specific embodiment 45 of my invention I desire it to be understood that I do not thereby wish to limit myself unnecessarily as various modifications falling wholly within the spirit and scope of my invention will readily suggest them-

selves to those versed in the art. What I 50 claim, therefore, as new and desire to secure by Letters Patent, is:—

1. In a fire-escape apparatus, the combination of a wagon body, a turntable upon said body, upright brackets on said turntable, extensible chute members mounted on said brackets, adjusting means connecting said chute and turntable for varying the inclination of the chute and lazy-tong members for extending and retracting said chute 60 members.

2. In a fire-escape apparatus, the combination of a wagon body, a turntable upon said body, upright brackets on said turntable to be turned therewith, a main chute 65 member pivotally mounted on said brackets, a plurality of consecutively smaller chute members slidably mounted and supported by said main chute member, lazy-tong members mounted on said main chute member 70 and pivotally connected to each of said smaller chute members and means for quickly extending and collapsing said lazy-tongs and the associated chute members.

3. A fire-escape apparatus comprising a 75 main chute member curved at one end, a basket for said curved end, a plurality of auxiliary chute members mounted to slide telescopically within said main chute member, pivot members secured to one end of 80 each of said auxiliary members, expandible members attached to said pivot members and operating means carried on said main chute member for quickly collapsing and extending 85 said auxiliary members.

4. A fire-escape apparatus comprising a main chute member, a plurality of auxiliary chute member mounted to slide telescopically within said main chute member, said chute members being substantially **U**-shaped in cross-section, guide bars uniting the sides of said chute members and lazy-tong members for rapidly extending and collapsing said chute sections.

In testimony whereof I have hereunto set 95 my hand on this 28th day of September A. D., 1921.

MARIUS ROSGAARD.
